UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARP GUIDE FOR COMBS.

Application filed November 9, 1923. Serial No. 673,702.

To all whom it may concern:

Be it known that I, ALONZO E. RHOADES, a citizen of the United States, and a resident of Hopedale, county of Worcester, State of Massachusetts, have invented an Improvement in Warp Guides for Combs, of which the following description, in connection with the accompanying drawing, is a specification, like characters on the drawing representing like parts.

This invention relates to metal warp guides such as are employed in the combs of warpers and slashers.

The object of the invention is to provide a simple form of such warp guide so constructed that when a series of warp guides are in position all of the dents will be exactly in line throughout and thus prevent the warp threads from becoming crossed and insure that each warp thread shall be guided in precisely the same manner and in substantial parallelism.

The object of the invention is further to provide such a sheet metal warp guide which shall be formed integral throughout of a single piece of sheet metal.

These and other objects and features of the invention will appear more fully from the accompanying description and drawings and will be particularly pointed out in the claim.

In the drawings:

Fig. 1 is a transverse section of a portion of a comb showing one of the warp guides embodying a preferred form of the invention in place.

Fig. 2 is a view in front elevation of the warp guide shown in Fig. 1.

Fig. 3 is a view in side elevation of the warp guide shown in Fig. 1 looking at the opposite side.

Fig. 4 is a view in rear elevation of the same warp guide,

Fig. 5 is an enlarged top plan view of a series of warp guides as positioned in the comb with the warp threads guided thereby.

The comb herein illustrated in connection with a disclosure of the present invention is of a similar construction to that shown in my prior Patent 818,560, granted April 24, 1906, and as the general construction of such combs is well known and familiar to those skilled in the art no detailed description thereof is necessary. In that construction

each warper guide presents a long bottom shank held between the expansible spring holding device 1 and a pair of dents which are arranged parallel to and separated from each other both laterally and fore and aft so that one dent is located well forward of the other in the direction of travel of the warp.

In the construction of the present invention each warp guide comprises a single bottom shank and a pair of warp dents but these warp dents are arranged not only parallel to each other but directly opposite to each other so that when the warp guides are assembled in the series in the comb all of the dents are exactly in line and thus the action of each dent in guiding the warp is precisely the same and all danger of crossing of the warp threads in the comb or further along in their travel is prevented and thus the accurate guidance of the entire sheet of warp threads is secured.

The warp guide of this invention is formed entirely of a single integral piece of sheet metal. Thus the warp guide may readily be punched out and bent into the required shape requiring no soldering, welding or other additional operations and requiring no additional features of construction in order to enable it satisfactorily and efficiently to perform its functions.

In the construction illustrated as an embodiment of a preferred form of the invention the warp guide comprises a flat shank 2 and a flat dent 3 forming a prolongation of the shank and lying in the plane of the shank. A second flat dent 4 is of the same shape as the dent 3 but is laterally offset from the first dent. The two dents have their flat faces parallel and are disposed exactly opposite to each other, or in other words, the central longitudinal axes of the dents both lie in a plane normal to the said faces. A substantially semi-cylindrical portion 5 of the sheet metal from which the warp guide is formed connects the upper end of the shank 2 with the lower end of the dent 4. The axis 6 of this semi-cylindrical portion 5 extends parallel to and midway between the dents. This semi-cylindrical portion merges the upper end of the shank 2 into the dent 4.

In the construction of the guide the entire device is first stamped or punched out of sheet metal while in a flat condition. The portion forming the dent 4 is then bent into

parallelism with the dent 3 thus forming the semi-cylindrical portion 5 which unites the dent 4 with the shank 2.

The upper edge 7 of the semi-cylindrical portion 5 forms a smooth bridge between the two dents at their bases and prevents any danger of the warp threads from being caught or pinched between the dents.

When the dents thus made are assembled 10 in the comb they stand in a continuous series directly in line as shown by the plan view in Fig. 5 and each acts to guide the threads 8 in the same manner. Thus any danger of the warp threads being crossed between the different dents or during their onward travel 15 is prevented and the accurate guidance of the warp threads is insured.

The construction of the warp guide is extremely simple and is one which can be readily and easily manufactured. There is no 20 danger of the warp threads being caught, worn or chafed by any portion of the warp

guide and there is no danger of separation of the one dent from the other.

Having thus described the invention, what 25 is claimed as new and desired to be secured by Letters Patent, is:

As a new article of manufacture an integral, one piece sheet metal warp guide comprising a flat shank, a flat dent forming 30 a prolongation of the shank, a second similar flat dent laterally offset from the first dent, the two dents having their flat faces parallel with the central longitudinal axes of the dents lying in a plane normal to the said 35 faces, and a substantially semi-cylindrical portion having its axis parallel to and midway between said dents and merging the upper end of the shank into the lower end of the second dent. 40

In testimony whereof, I have signed my name to this specification.

ALONZO E. RHOADES.
